UNITED STATES PATENT OFFICE.

CHARLES B. SLADE, OF NEW YORK, N. Y., ASSIGNOR TO ETHICUS PROMPT TREATMENT KIT, INC., OF NEW YORK, N. Y., A CORPORATION OF NEW YORK.

PROMPT-TREATMENT KIT.

Application filed November 7, 1922. Serial No. 599,581.

To all whom it may concern:

Be it known that I, CHARLES B. SLADE, a citizen of the United States of America, and a resident of the city, county, and State 5 of New York, have invented certain new and useful Improvements in Prompt-Treatment Kits, of which the following is a description.

My invention relates to a kit adapted to 10 hold conveniently pill boxes or like small articles.

The primary and essential features of 15 which are, briefly, a kit box, to hold several different remedies or medicines, with a separate compartment for each remedy; each and every one of these compartments having a separate and distinct exterior cover or door, so arranged and labeled that when a particular remedy is sought, only that 20 remedy is exposed; so that the possibility of confusion, or taking the wrong medicine by accident is eliminated, making it, to this extent, error-proof.

Further objects and advantages of my 25 invention will be apparent from the following specification taken with the accompanying drawing in which—

Figure 1 is a perspective view of a device according to my invention.

Figure 2 is a perspective view of my said 30 device looking in the opposite direction from Figure 1, parts being broken away for purpose of illustration.

Figure 3 is a vertical section on the line 35 3—3 of Figure 1.

Figure 4 is a horizontal section on the line 4—4 of Figure 3 looking in the direction of the arrows.

In the drawing, 1 is a base of wood or 40 other rigid and relatively heavy material which helps to maintain the stability of the complete article as well as to protect and help hold together the lighter parts comprising the remainder and major portion 45 of the article.

Above base 1 are three paste-board or like boxes indicated on the drawing by 2, 3 and 4, respectively arranged with their major dimensions perpendicular to base 1 so that 50 they normally stand on their ends. Box 2 has a width equal to that of base 1 and opens outwardly from the base, one edge of box 2 being even with one of the outer edges of the base 1.

Boxes 3 and 4, as clearly appears in Fig-

ure 4, are arranged facing in opposite directions and facing or opening in directions at right angles to the direction or opening of box 2, boxes 3 and 4 having one side placed against what would ordinarily be 60 used as the bottom of the box 2. Boxes 2, 3 and 4 are secured together and also secured to base 1, if such base is used, by a circumferential strip 5 of "leatherette" or similar moderately stiff material, which can be 65 readily glued to parts to be held together. Strip 5 extends only partway up the lengths of boxes 2, 3 and 4 so that it does not interfere with placing articles into the kit. Across their ends opposite the base 1 boxes 70 2, 3 and 4 are also secured together by a rectangular piece of paste-board 6 or like 75 relatively stiff but light material. The boxes 2, 3 and 4 are preferably further secured together by strips of paper or like 80 material, preferably in the form of imitation leather or "leatherette." One of such strips is indicated at 7 and extends from the inner surface of box 2 at 7^a around one outer side of box 2 and into interior of box 3 at 85 7^b. A second such strip is indicated at 8 and extends from the inner side or face of box 2 at 8^a on one edge thereof around the outer side of box 2 and into box 4, at 8^b. Strips such as 7 and 8 being glued or pasted 90 to the box materially increase the strength of the completed article.

As clearly appears in Figure 4, the depth of boxes 3 and 4 is such that there is a space between them indicated at 9, this serving, by virtue of the strip 5 and other means to be hereafter described, as the equivalent of a fourth box or receptacle, when the kit is in use.

Across the top of the kit over the reinforcing plate or piece 6 is a piece 10 of "leatherette" or other suitable material. Piece 10 is of flexible material and has four integral flaps thereon adapted to extend down the sides of the kit and cover the openings of boxes 2, 3 and 4 as well as the space 9. The flap for box 2 is indicated on the drawing by the character 2^a; that for box 3 by 3^a; that for space 9 by 9^a; and that for box 4 by 4^a. These flaps are normally 100 held down as indicated in Figures 1 and 2 by means of fasteners which may be of any convenient type, those illustrated being of the ordinary glove fastener type. Due 105 to the flexibility of the material of piece 10 110

the flaps for the various boxes may be readily lifted as indicated in dotted lines in Figure 1.

5 The lower portion of boxes 2, 3, 4 or 9 may be filled with cardboard as indicated at 11 in box 2 to prevent pill-box 12 or similar articles which may be placed in the kit from dropping down too far to prevent their ready removal.

10 Preferably the interior of boxes 2, 3, and 4, the sides of the space 9 and bottom of base 1, are covered by paper or similar material in imitation of leather.

15 Preferably the flaps 2^a etc. bear approximate legends indicating the article or material to be kept in the various spaces or receptacles of the kit. The device being particularly well adapted for storing medicines, I have illustrated the flaps as bearing 20 the names 13 of common ailments for which remedies are ordinarily kept in the average household.

25 Referring again to the means by which flaps 2^a, 3^a, 4^a, and 9^a are held over the mouths of the boxes and over space 9, I have illustrated this means as comprising knobs 5^a carried on band 5, and sockets 2^b, 3^b, 4^b, and 9^b, carried on flaps 2^a, 3^a, 4^a, and 30 9^a respectively and adapted to snap over the corresponding knobs on band 5.

35 It is evident that a kit according to my invention is not only highly useful in the average household but is also well adapted to the needs of the average practicing physician or pharmacist.

40 While I have described above in detail a given form of device according to my invention, I do not wish to be limited to details of my disclosure herein, except in so far as such details are essential to the novelty of the appended claims.

Having thus described my invention I claim:

45 1. A multi-pocket kit comprising in combination a relatively large box, a relatively small box having one side held against what is ordinarily the bottom of said large box and opening in a direction at right angles to that in which said larger box opens, a second relatively small box also abutting against said large box, but facing in the direction opposite from said first small box, pieces fastened across the ends of said boxes, a band around said boxes at their one ends, flaps hinged to said boxes at their other ends, and means whereby said flaps may be releasably fastened over the openings of said boxes.

50 2. A multi-pocket kit comprising in combination a relatively large box, a relatively small box having one side held against what is ordinarily the bottom of said large box and opening in a direction at right angles to that in which said larger box opens.

55 60 65 3. A second relatively small box abutting

against said large box but facing in the direction away from said first small box and spaced therefrom, pieces fastened across and covering the ends of said boxes, a band around said boxes at their one ends, four flaps hinged to said boxes at their other ends and means whereby said flaps may be releasably fastened over the openings of said boxes.

3. A multi-pocket kit comprising in combination a relatively large box, a relatively small box having one side abutting against what is ordinarily the bottom of said large box and opening in a direction at right angles to that in which said large box opens, a second relatively small box also abutting against said large box and opening outwardly, a cover piece fastened across the one ends of said boxes, a relatively heavy base fastened across the other ends of said boxes, a band around said base and boxes at the base end thereof, flaps hinged to said boxes at the ends opposite said base, and adapted to cover the openings of said boxes and means on said band adapted to assist in releasably fastening said flaps over the openings of said boxes.

4. A multi-pocket kit comprising in combination a relatively large box, a relatively small box, having one side abutting against what is ordinarily the bottom of said large box and opening in a direction at right angles to that in which said larger box opens, a second relatively small box also abutting against said large box but spaced from said first mentioned small box and opening in the opposite direction therefrom, pieces fastened across the one ends of said boxes, a relatively heavy base fastened across the other ends of said boxes, a reinforcing band fastened around said base and said boxes at their base ends, four flaps hinged to said boxes at their ends opposite said base and means whereby said flaps may be releasably fastened over the openings of said boxes.

5. A multi-pocket kit comprising in combination a relatively large box, a relatively small box having one side abutting against what is ordinarily the bottom of said large box and opening in a direction at right angles to that in which said larger box opens, a second relatively small box also abutting against said large box but spaced from said first mentioned small box and opening away from it, a piece fastened across the one ends of said boxes, a relatively heavy base fastened across the other ends of said boxes, a reinforcing band fastened around said base and around said boxes at their base ends, a second piece fastened above said piece at the ends of the boxes opposite the base, four flaps hinged to said last mentioned piece and adapted to cover the openings of said boxes and said space and means whereby said flap

may be releasably fastened to said reinforcing band.

6. A multi-compartment kit comprising in combination a square base, a plurality of boxes standing on end on said base and opening outwardly, said boxes being fastened to said base, a reinforcing band around said base and around the base ends of said boxes, means in addition to said base for fastening said boxes together, flaps hinged at the end of the kit opposite said base and adapted to cover the openings of said boxes and fastening means carried at least in part on said band for releasably holding said flaps to close said boxes.

7. A multi-compartment kit comprising in combination a plurality of boxes fastened together with their longitudinal axes parallel, said boxes opening outwardly, a piece fastened across said boxes at one end, and flaps hinged to said piece and adapted to cover the openings of said boxes.

8. A multi-pocket kit comprising in combination a relatively large box, a relatively small box, having one side held against what is ordinarily the bottom of said large box

and opening in a direction at right angles to that in which said larger box opens, a second relatively small box held against said large box but facing in the opposite direction from said small box, a band around said boxes at their one ends, flaps hinged to said boxes at their other ends, and means whereby said flaps may be releasably fastened over the openings of said boxes.

9. A multi-pocket kit comprising in combination a relatively large box, a relatively small box having one side thereof held against what is ordinarily the bottom of said large box and opening in a direction at right angles to that in which said larger box opens, a second relatively small box also held against said large box, said second small box being spaced from the said first mentioned small box and facing in the opposite direction therefrom, a band around said boxes at their one ends, four flaps hinged to said boxes at their other ends and means whereby said flaps may be releasably fastened over the openings of said boxes and over the space between said small box.

CHARLES B. SLADE.
